UNITED STATES PATENT OFFICE

2,510,157

ELECTROMAGNETIC RELAY

Stanley Herbert Towner and Percy Arthur Childs, London, England, assignors, by mesne assignments, to International Standard Electric Corporation, New York, N. Y., a corporation of Delaware

Application July 25, 1944, Serial No. 546,545
In Great Britain July 7, 1943

Section 1, Public Law 690, August 8, 1946
Patent expires July 7, 1963

9 Claims. (Cl. 200—104)

1

This invention relates to electromagnetic relays.

Among the objects of the invention is that of reducing the deleterious effects upon the relay and its operation of mechanical vibration or shock. It has been found with electromagnetic relays of known types that the stability and operation of their contacts are adversely affected by mechanical vibration or shock, possibly due to the production of relatively large linear accelerations of the movable parts, and a design is required in which such effects are of negligible magnitude. Whether or not the above tentative explanation is correct, it has certainly been found that designs in accordance with the present invention do show improvement in these respects.

Another important object of the invention is to provide a novel and advantageous electromagnetic relay.

A further object of the invention is to provide a novel and advantageous electromagnet-and-armature device.

This invention includes an electromagnetic relay comprising a substantially flat armature pivoted near its center and arranged so that the operating force and contact load are applied on opposite sides of the pivot, and so that the gravitational moments of the masses of the moving parts are substantially balanced about the pivot.

The invention will now be described with reference to the accompanying drawing, which shows by way of example one embodiment. In the drawing:

Fig. 1 is a view in side elevation;

Fig. 2 is a left-hand end view;

Fig. 3 is a right-hand end view;

Fig. 4 is a top-plan view with the contact-spring pile-up removed to expose the armature; and

Fig. 5 is a view in longitudinal central section.

In the drawing is shown the usual relay winding 11 mounted upon a soft-iron core 12 of which the forward projecting end is turned up and then back to form a pole-piece 13 with its flat uppermost surface constituting the pole-face. Tightly fitting over, and preferably welded to, the rearward projecting end of the core 12 is a yoke 14 extending upwardly and forwardly along the top of the winding 11 to within a short distance of the pole-piece 13. The armature, which will be more particularly described, is shown at 15 bridging the gap between yoke 14 and pole-piece 13: the contact-spring pile-up is shown at 16.

Referring more particularly to Figs. 1, 4 and 5, 55

2

it will be seen that the armature 15 is almost but not quite flat when viewed edgewise and that it lies in a plane substantially parallel with those of the contact-springs of the pile-up 16.

5 A D-shaped opening is cut away in the rearward half, leaving a frame-like tail 17 that normally rests upon the supporting stop 22, for engagement with the lifting pins 18 on the pile-up 16. This tail is bent slightly upwards with respect to the plane of the remainder of the armature. Of the solid forward half of the armature, the most rearward part lies between the flanks of the D-shaped tail-frame and terminates in a knife edge 19 which lies slightly below the level 10 of the tail and which therefore is able to constitute the pivot for the armature as it rests upon the upper surface of the yoke 14 with its solid forward half overlying the pole-face on the piece 13. Energization of the coil 11 15 causes the forward end of the armature 15 to be attracted downwardly to the pole-piece 13, the armature turning about the edge 19 so that the tail 17 rises from the stop 22 and through the intermediary of the lifting pins 18 causes operation of the contacts of the pile-up 16. Thus the operating force and the contact load are applied on opposite sides of the pivot.

The armature pivots on its edge across almost the full width of the relay, making an iron to iron contact with the yoke which it overlaps to provide a low reluctance hinge joint.

The armature is permanently located in its correct position by means of light leaf springs 20. As shown there are two of these springs 35 formed integral with a single cross piece and extending parallel with the longitudinal axis of the armature, that is at right angles to the pivotal axis 19. They thus underly the flanks of the D-shaped tail-frame of the armature. At 40 their forward ends they are welded to the underside of the armature, and at their rearward ends they are welded to the top surface of the yoke 14. Beryllium-copper is a suitable material for the springs.

45 Preferably the dimensions of the armature locating springs are chosen so that the forces exerted by them on the armature over the full range of armature movement are small relative to those due to the contact springs in the pile-up 16. The springs are not by themselves strong enough to perform the usual retractile function, and reliance must be placed primarily upon the resilience of the contact-springs, in the usual manner. However, the additional springs 20 may be biased so as to ensure that the knife edge

on the armature seats always on the yoke, thus avoiding hammering upon the knife edge.

It is a feature of this invention that the gravitational moments of the masses of the moving parts are substantially balanced about the pivot 19. That is to say, the mass of the front portion of the armature produces at the pivot a moment which is just about equal to the moment produced by the mass of the tail part, together with the lifting pins, and the moving contact springs down to their roots. By reason of this feature, a mechanical shock in the vertical direction (which is the worst case) produces equal and opposite accelerations about the pivot so that there is substantially no resultant torque that would cause improper operation or release of the armature.

The contact unit is fixed to the magnet system by a single screw 21 passing through the moulding, acting as support of the contact spring pile-up 16, into the yoke, and is located at the forward end by two steps in the moulding which fit over the edge of the pole face. This means that the pile-up constitutes an independent unit, and that, in particular, its adjustment can be carried out before assembly with the remainder of the relay. As indicated in Figs. 1, 2 and 3, the moulding of the contact-spring pile-up 16 has a wide forward portion above the pole-piece 13 and a narrower portion extending rearwardly between the contact-springs which are clamped at the sides of said wide portion.

The forward portion of the yoke 14 is set down slightly below the pole face so that the tightening of the screw 21 pulls the yoke parallel to the pole face, the registration being controlled by the moulding and being maintained by the pressure at the rear end.

The flat shape of the armature and its location between the winding and core assembly below and the contact-spring pile-up assembly above, affords the armature some measure of protection against mechanical contact.

What is claimed is:

1. In an electromagnetic device, the combination of a pole-piece with a flat contact surface and a second pole-piece with a contact surface in alignment with said flat contact surface, an armature having two arms, both said arms arranged above and extending along said two pole pieces, one of said arms with a flat pole-piece bridging surface and at an end thereof a knife edge pivot in the same plane as said bridging surface and adapted to rest on said flat contact surface, and the second of said arms offset outwardly from the plane of said bridging surface.

2. In an electromagnetic device, the combination of a pole-piece with a flat contact surface and a second pole-piece having a contact surface in alignment with said flat contact surface, an armature having a flat pole-piece bridging surface and at one end of this surface a knife edge pivot resting on said flat contact surface and bounded at one side by the plane of said flat pole-piece-bridging surface.

3. The combination according to claim 2, including means for maintaining the knife edge in position on the flat contact surface comprising a leaf spring attached at opposite sides of said pivot to said armature and to said pole piece with the flat contact surface.

4. In an electromagnetic device, the combination of a pole-piece with a flat contact surface

and a second pole-piece having a contact surface, means supporting said pole pieces for bringing said contact surfaces into alignment and an armature having a flat pole-piece-bridging surface and at one end of the bridging surface a knife-edge pivot resting on said flat contact surface and bounded at one side by the plane of said flat bridging surface.

5. In an electromagnetic device, the combination of a pole-piece with a flat contact surface and a second pole-piece having a contact surface, and an armature arm having a flat pole-piece-bridging surface and at one end of the bridging surface a knife edge pivot resting on said flat contact surface and bounded at one side by the plane of said flat bridging surface, and supporting means for bringing said contact surfaces into alignment and shielding said armature arm.

6. In an electromagnetic device, the combination of a pole-piece with a flat contact surface and a second pole-piece having a contact in alignment with said flat contact surface, an armature having two arms, both said arms arranged above and extending along said two pole pieces, one of said arms with a flat pole-piece-bridging surface and a tongue providing an extension of said flat bridging face and also a knife edge pivot resting on said flat contact surface, and the second of said arms presenting an actuating arm attached to the first arm and offset therefrom and from the knife edge pivot.

7. The combination according to claim 6 including means for maintaining the knife edge pivot in operative position comprising a leaf spring attached to said armature and to the pivot supporting pole piece, and means for swinging the armature to open position.

8. The combination according to claim 6 wherein the material of said armature is of uniform thickness from end to end.

9. In an electromagnetic relay, the combination of a pole face, an armature having two arms and pivoted at an intermediate point thereof one arm being substantially flat and having a central portion cut-out, a contact-spring pile-up comprising a moulding extending through the opening defined by the said cut-out, means to secure said moulding in position on said pole face and controlling means for said contact-spring pile-up engaging said one arm.
